OSCILLATION GENERATOR AND
FREQUENCY MULTIPLIERJohn L. Reinartz, Manchester, Conn., assignor to
Radio Corporation of America, a corporation
of Delaware

Application April 23, 1937, Serial No. 138,508

4 Claims. (Cl. 250—36)

This invention relates to oscillation generator and frequency multiplier circuit arrangements. Many circuit arrangements have been designed in the past with the object of producing oscillations at multiple frequencies of the fundamental frequency generator, but among the defects and deficiencies of such arrangements it has been found that either these devices produce output energy of a very low value or else 5 the arrangement has been found lacking stability. Furthermore, if it is attempted to multiply the fundamental frequency so as to obtain one of the higher harmonics, that is, above the third or fourth harmonic, the difficulty of maintaining 10 an exact ratio between the output and the fundamental frequency of the generator is very much increased.

It is among the objects of my invention to provide a circuit arrangement including a fundamental frequency oscillation generator and a frequency multiplier such that output energy of considerable amplitude may be obtained even when this output energy is multiplied to one of the higher harmonics of the fundamental frequency. 15

As a result of my experiments it has been proven that the tenth harmonic of the frequency of a generator having a piezo-electric crystal control may readily be obtained where only two 20 electron discharge tubes are employed. In carrying out my invention I was able to produce the aforesaid tenth harmonic with a circuit arrangement which delivered as much as 10 watts of this harmonic frequency. This was done without exceeding the normal plate dissipation. 25

It may readily be seen that the circuit arrangement which I am about to describe has considerable utility in short wave radio apparatus. If, for example, a piezo-electric crystal were to be 30 employed having a frequency rating of, say, 3.75 megacycles (which corresponds to a wave length of 80 meters), the tenth harmonic of this frequency would be suitable as a carrier wave of 37.5 megacycles, or 8 meters. This same crystal 35 is also likely to prove useful in a circuit in which the sixteenth harmonic would be developed and where the output frequency would thus be a 5 meter wave, that is, a wave having a frequency of 60 megacycles. 40

50 My invention will now be described in detail, reference being made to the accompanying drawing in which

55 Figure 1 shows a typical circuit arrangement having a fundamental frequency generator stage

and a frequency multiplier stage, each stage comprising an electron discharge tube,

Fig. 2 shows a modification of the second or frequency multiplier stage, and

Fig. 3 shows still another modification in which 5 the two stages of oscillation generation and frequency multiplication are suitably coordinated with but one electron discharge tube of the twin triode type.

Referring to Fig. 1, I show an electron discharge tube 1 preferably of the pentode type in which are a cathode 2, a control grid 3, a screen grid 4, a suppressor grid 5, and an anode 6. The input circuit for this tube includes a grid leak resistor 7 and a radio frequency choke 8 in circuit between the control grid 3 and ground. The cathode 2 is coupled to ground by means of a capacitor 9 which may, if desired, be made adjustable. Furthermore, the capacitor 9 and the choke 8 in combination form a tank circuit 20 which may be tuned to one-half of the fundamental frequency of the oscillations to be generated in the tube 1. This fundamental frequency is the frequency at which a piezo-electric element 10 is adapted to vibrate. The element 10 is connected in shunt with the resistive and reactive elements 7 and 8 respectively. 25

The tube 1 has its screen grid 4 biased at a suitable positive potential with respect to the cathode 2, this biasing being provided by means 30 of a potentiometer 11 across the positive and negative terminals of a suitable direct current source, as indicated by the plus and minus signs. The anode 6 derives positive potential from this source, the connection to the anode being made 35 through the primary coil 12 which forms with the capacitor 13 a tank circuit tuned to the fundamental frequency of the generator. A by-pass condenser 14 is preferably connected between the screen grid lead and ground. Another by-pass 40 condenser 15 forms a coupling connection between the positive side of the D. C. source and ground. The negative side of this source is, of course, grounded. 45

The circuit arrangement thus far described 45 constitutes an oscillation generator, having its component parts so adjusted as to develop a high frequency, the constancy of which is controlled by the piezo-electric device 10.

The anode 6 of the tube 1 is coupled by means 50 of a capacitor 16 to the control grid 17 of an electron discharge tube 18 in a second stage of the circuit arrangement. This second stage serves as a frequency multiplier. The input circuit for the tube 18 includes a radio frequency 55

choke 19 in series with a grid leak resistor 20, these two elements being connected between the grid 17 and the grounded cathode 21. The anode 22 is fed with current from the positive side of 5 the direct current source through the secondary transformer winding 23. This secondary winding forms with the adjustable capacitor 24 a tank circuit tuned to a desired harmonic frequency of the fundamental frequency generated 10 in the tube 1. The coupling between the primary 12 and the secondary 23 is preferably made adjustable.

Output energy at the desired harmonic frequency is taken off through a blocking condenser 15 25 whence it is carried to any suitable utilization device, not shown.

In order to appreciate the novel features of my invention attention should be directed to the coupling arrangement between the output circuits 20 of the two tubes. This coupling between the primary winding 12 and the secondary winding 23 provides a mode of operation which has an 25 analogy in the swinging of two pendulums, one at a fundamental frequency and the other at a frequency harmonically related thereto. The adjustment is such that the slow pendulum gives an impulse to the fast pendulum as often as their 30 respective oscillations are in phase. Power output from the fast pendulum can be obtained at any harmonic rate. It will thus be seen that the second stage of my circuit arrangement is enabled to deliver considerably more power than would otherwise be the case merely by virtue 35 of the boosting effect of the output energy from the fundamental frequency generator impressed across the intercoupling transformer. This desirable result is only obtained, however, when the proper phase relationship exists between the transformer coupling and the coupling between 40 the anode 6 of the first stage and the control grid 17 of the second stage, that is, through the capacitor 18.

It has been observed that in the operation of this circuit the disconnection of the piezo-electric device causes oscillations to cease both in the fundamental frequency generator and in the frequency multiplier stage.

Referring to Fig. 2, I show the substitution of a screen grid tube 26 for the triode tube 18 of Fig. 1. It will be seen that this screen grid tube 26 is connected to the portion of the circuit lying to the left of the dot and dash line a—a in the same manner as has been heretofore described with respect to the tube 18. It 50 only need be mentioned here, therefore, that the screen grid electrode 27 is supplied with a suitable positive potential with respect to the cathode 21 and that preferably the screen grid should be provided with a by-pass condenser 28 constituting a radio frequency path to ground. In 55 other respects the operation of the circuit arrangement shown in Fig. 2 will be fully appreciated from the foregoing description of Fig. 1.

Referring to Fig. 3, I show a twin triode electron discharge tube 30 having a common cathode 31, a grid 32 and an anode 33 in one triode portion, and a grid 34, an anode 35 in the other triode portion. Considering the electrodes 31, 32, 33, it may be seen that these are connected 60 to input and output circuits respectively in the same manner as is shown in Fig. 1 with respect to the tube 1, that is to say, there is a grid leak resistor 7 connected between the grid 32 and the cathode 31. There is also a piezo-electric device 10 connected between the grid 32 and

ground. Furthermore, there is an adjustable capacitor 9 forming with the choke 8 a tank circuit tuned to one half of the fundamental frequency of the oscillation generator and of the piezo-electric device 10, this tank circuit being connected 5 between the cathode 31 and ground. The anode 33 is connected to a positive d-c potential source through the primary 12 which forms with the adjustable capacitor 13 a suitable tank circuit tuned to the fundamental frequency. Referring 10 to the electrodes 31, 34, 35, it will be seen that these are connected to input and output circuits of a second stage, that is, a frequency multiplier stage, in the same manner as is shown for the tube 18 in Fig. 1. Thus, the grid leak resistor 15 19 and the choke 20 are provided in the input circuit. The anode 35 is supplied with d-c positive potential through the transformer secondary 23, which secondary forms with the capacitor 24 a suitable tank circuit tuned to the desired harmonic frequency. The by-pass condenser 25 permits harmonic frequency energy to be taken off and lead to any suitable utilization device. The 20 operation of the circuit arrangement of Fig. 3 will now be clearly understood from what has 25 been said with respect to Fig. 1.

In connection with a specific embodiment of my invention as shown in Fig. 1, and as has been found to be suitable for generating a fundamental frequency of 3.55 megacycles and where 30 the eighth harmonic thereof or 28.4 megacycles was developed in the output circuit of the multiplier stage, the following values have been found to be suitable:

In the input circuit of the tube 1 the grid 35 leak had a value of 5,000 ohms. The choke in series therewith had a value of 100 microhenrys. The capacitor had a value of 100 micromicrofarads.

In the input circuit for the multiplier stage 40 the grid leak resistor had a value of 50,000 ohms. The radio frequency choke in series therewith was of such value as to substantially prevent the leakage of high frequency energy to ground. The power output from the frequency multiplier stage 45 was in the neighborhood of 10 watts when this stage was tuned to the eighth harmonic. The frequency thus delivered was 28.4 megacycles.

It will be understood that the circuit arrangements as herein shown and described are merely 50 illustrative of numerous circuit arrangements of a general type coming within the scope of my invention.

I claim:

1. An oscillation generator and frequency multiplier comprising an electron discharge tube circuit arrangement constituted by two stages each having an input portion including a control grid, an output portion including an anode, and a cathode system common to both portions in the 55 two stages, a source of direct current operating potentials suitably connected to said input and output portions, a tuned resonant circuit connected between the cathode system and the grounded negative terminal of said source, a 60 piezo-electric device connected between the control grid of the first stage and ground, a grid leak resistor connected between each control grid and the cathode system, a reactance in series with that one of said resistors which is in the second 65 stage, two resonant circuits having adjustably intercoupled inductances and adjustable capacitors, one of said resonant circuits being in the 70 output portion of the first stage and the other in the output portion of the second stage, a ca- 75

- pacitor coupling the anode of the first stage to the control grid of the second stage, means for so adjusting the two resonant circuits of the input and output portions in the first stage that oscillations are generated at a fundamental frequency under control of said piezo-electric device, and means for so adjusting the resonant circuit of the output portion in the second stage that oscillations are generated therein at a harmonic of said fundamental frequency.
2. A device according to claim 1 and further characterized in that there is but one electron discharge tube of the twin triode type in said circuit arrangement.
- 15 3. A two-stage electron discharge tube circuit arrangement comprising tuned input and output circuits for the first stage and a tuned output circuit for the second stage, the first stage constituting an oscillation generator and the second stage a frequency multiplier, a piezo-electric device for controlling the fundamental frequency of the oscillations generated, a tank circuit resonant to one half of said fundamental frequency connected in series with said piezo-electric device 20 in the input circuit of said first stage, a grid leak resistor in shunt with said series connection, ca-

pacitive coupling means between the output circuit of the first stage and the input circuit of the second stage, and inductive coupling means between the output circuits of the two stages, said output circuits being tuned to different harmonically related frequencies.

4. A circuit arrangement having a single electron discharge tube the cathode of which in combination with a first grid and a first anode constitute oscillation generator electrodes and the same cathode in combination with a second grid and a second anode constitute frequency multiplier electrodes, a tuned circuit and a piezo-electric device serially disposed in an input connection between the cathode and first grid, said 15 tuned circuit being resonant to one half the natural oscillation frequency of said piezo-electric device, inductively intercoupled output circuits connected from the cathode to the two anodes respectively, said output circuits being tuned to different harmonically related frequencies one of which is substantially the same as said frequency of the piezo-electric device, and capacitive coupling means connected between said first anode and said second grid.
